(57) **CLAIM**

The ornamental design for a circulator cooker clamp, as shown and described.

DESCRIPTION

FIG. 1 is a top front isometric view of a circulator cooker clamp showing our new design;

FIG. 2 is a bottom rear isometric view thereof;

FIG. 3 is a front view thereof;

FIG. 4 is a rear view thereof;

FIG. 5 is a right side view thereof;

FIG. 6 is a left side view thereof;

FIG. 7 is a top plan view thereof as viewed along line 7-7 in FIG. 6; and,

FIG. 8 is a bottom plan view thereof.

The broken lines in the drawings are for the purpose of illustrating unclaimed portions of the circulator cooker clamp and form no part of the claimed design. The dash-dot-dot lines indicate boundaries of the claimed design.
